US0D1043105S

(12) United States Design Patent (10) Patent No.: US D1,043,105 S
(45) Date of Patent:  Sep. 24, 2024

(54) BAG

(71) Applicant: MCM GLOBAL AG, Zug (CH)

(72) Inventors: SungJoo Kim, Seoul (KR); Youngnan Jang, Seoul (KR); Sooyeon Lee, Seoul (KR); Jihyun Nam, Seoul (KR); Hey Min Park, Seoul (KR); Sanghee Lee, Seoul (KR); Sun Young Ahn, Seoul (KR); Sang Mi Lee, Seoul (KR); Eun Soo Choo, Seoul (KR); Jihye Lim, Seoul (KR)

(73) Assignee: MCM GLOBAL AG, Zug (CH)

() Term: 15 Years

(21) Appl. No.: 29/859,549

(22) Filed: Nov. 10, 2022

Related U.S. Application Data

(62) Division of application No. 35/511,923, filed on Nov. 26, 2020 (U.S. filing date under 35 U.S.C. 384), and having an international filing date of Nov. 26, 2020, now Pat. No. Des. 975,434.
